UNITED STATES PATENT OFFICE.

HENRY G. VOIGHT, OF NEW BRITAIN, CONNECTICUT, ASSIGNOR TO THE RUSSELL & ERWIN MANUFACTURING COMPANY, OF SAME PLACE.

DESIGN FOR A LATCH-CASE.

SPECIFICATION forming part of Design No. 31,928, dated December 5, 1899.

Application filed November 7, 1899. Serial No. 736,191. Term of patent 7 years.

To all whom it may concern:

Be it known that I, HENRY G. VOIGHT, a citizen of the United States, residing in New Britain, in the county of Hartford and State 5 of Connecticut, have invented and produced a new and original Design for a Latch-Case, of which the following is a specification, reference being had to the accompanying drawings, in which—

10 Figure 1 is a perspective view of a latch-case, showing my new design. Fig. 2 is a transverse section of the same through the middle portion of the case.

15 As shown in the drawings, the front of the case is bordered by a double bead 3 3, the face-plate end of the case having right-angular corners 4 and the opposite end having slightly-rounded corners 5. The two longer sides 6 6 and one shorter side or end 7 have an

ogee form in cross-section, so that they curve 20 inwardly at their base 12, Fig. 2, as shown. Said sides are also provided with screw-hole bosses 8 of the shape shown. The face-plate or head end 9 of the latch has the same general form as the cross-section of the case, with 25 its outer and end edges 10 11 rounded into a bead form, as shown. The rear cap-plate 13, Fig. 2, is plain.

Having described my invention, what I claim as new, and desire to secure by Letters 30 Patent, is—

The design for a latch-case as herein shown and described.

HENRY G. VOIGHT.
